UNITED STATES PATENT OFFICE.

FREDERICK W. STEIN, OF JERSEY CITY, NEW JERSEY.

CHIMNEY-COWL.

SPECIFICATION forming part of Letters Patent No. 733,762, dated July 14, 1903.

Application filed November 25, 1902. Serial No. 132,762. (No model.)

To all whom it may concern:

Be it known that I, FREDERICK W. STEIN, a citizen of the United States, and a resident of Jersey City, in the county of Hudson and State of New Jersey, have invented a new and Improved Chimney-Cowl, of which the following is a full, clear, and exact description.

The object of this invention is to provide a chimney-cowl which will insure an effective draft through the flue. This end is attained by providing a cowl with means forming an air-duct leading upward from the back of the cowl, over the top thereof, thus causing the gases or smoke to be drawn upward through the flue and out of the cowl with the before-mentioned current of air.

This specification is an exact description of one example of my invention, while the claim defines the actual scope thereof.

Reference is to be had to the accompanying drawings, forming a part of this specification, in which similar characters of reference indicate corresponding parts in both views.

Figure 1 is a perspective view of the invention, and Fig. 2 is a vertical section thereof.

a indicates the flue or smoke-pipe, which is fitted at its top with a spider *b*, and below the spider *b* is a spider *c*, these spiders carrying the spindle *d*. Said spindle has a downwardly-directed pin *d'*, bearing in the spider *c* to prevent lateral movement of the pin. Anti-friction-bearing devices *d''* are provided to sustain the pin on this spider. The spindle *d* passes up laterally through the spider *b* and is provided with a collar *d'*, which prevents the upward displacement of the pin. A cross-bar *e* is attached to the upper end of the spindle *d*, and this bar has its ends fastened to the body *f* of the cowl. By this arrangement the body or part *f* of the cowl is held to turn with the spindle *d* in the position shown in the drawings. A bead *a'* is formed around the upper end of the flue *a*, and against this bead the concentric lower part of the cowl proper, *f*, bears snugly, so that it is impossible for any appreciable current of air to pass between the cowl *f* and the stack or flue *a*. The cowl proper may, however, be turned at will to any position around the circumference of the pipe.

g indicates the top member of the cowl, which is set at an inclination to the cowl proper, *f*,

and has its side corners *g'* fastened by riveting, soldering, or otherwise to the sides of the cowl proper, *f*, these parts *f* and *g* being so arranged that an air-space *i* is provided between the top of the cowl proper, *f*, and the bottom of the section *g*, said section *g* extending upward considerably above the cowl proper, *f*, and carrying at its upper end the usual blade *k*, which causes the cowl to be turned by the wind into the position desired.

The cowl proper, *f*, is formed of a sheet of metal curved longitudinally and set at an inclination to the vertical, so as to deflect the draft from the chimney *a* in essentially the usual manner. The top member *g* is also formed of a metal sheet curved to correspond with the cowl proper, but on a sharper arc, so that when set on the cowl proper its side corners touch the cowl proper, as described above, and the middle portion is spaced therefrom to form the passage *i* referred to. Also it may be observed from Fig. 2 that the member *g* sets at an inclination to the cowl proper, thus giving the passage *i* a flare toward the rear.

With the construction above described the cowl turns readily by the force of the wind, so as to present its back thereto, and the smoke from the pipe *a* passes out from under the cowl proper, *f*. Simultaneously a current of air is forced through the passage *i* and escapes just over the top of the cowl proper, *f*. This current of air draws the smoke with it, and thereby increases the draft up the flue *a*.

Various changes in the form, proportions, and minor details of my invention may be resorted to at will without departing from the spirit and scope thereof. Hence I consider myself entitled to all such variations as may lie within the intent of my claim.

Having thus described my invention, I claim as new and desire to secure by Letters Patent—

In a chimney-cowl, the combination with the smoke-pipe or flue and with a rotating supporting means held thereby, of a cowl-body formed of sheet metal attached to said rotating supporting means and curved in an arc concentric to the cross-sectional form of the smoke-pipe, said cowl proper being engaged with the upper edge of the smoke-pipe to turn snugly around the same and slanting

diagonally with respect to the longitudinal axis of the pipe, and a top member formed of sheet metal curved on an arc sharper than that of the curvature of the cowl-body and lying over the cowl-body and spaced therefrom at the middle portion of the cowl-body, the side portions of the top member being secured to the side portion of the cowl-body.

In testimony whereof I have signed my name to this specification in the presence of 10 two subscribing witnesses.

FREDERICK W. STEIN.
